ART OF WARP KNITTING

Frank J. Kaufmann, Tribes Hill, N. Y.

Application December 17, 1941, Serial No. 423,271

8 Claims. (Cl. 66—86)

This invention relates to tricot warp knitting machines in which two or more threads are drawn from two or more warp beams that have different surface speeds to supply different lengths of thread running at different speeds to be knitted into the same length of cloth during a predetermined cycle of knitting movements of the machine.

The usual, but not by any means the only, cycle in such machines is one consisting of four hundred and eighty knitting movements and such cycle as well as the length of cloth produced during such cycle is generally referred to as a "rack." The expression "cycle of knitting movements" as hereinafter used is intended to cover not only a "rack" of four hundred and eighty movements but any other cycle consisting of a predetermined number of such movements and is also intended to include one or more "racks."

In machines of the character indicated, different lengths of thread drawn from different warp beams rotating at different surface speeds, are knitted into the same length of cloth in order to produce a certain amount of elasticity therein, and the amount of elasticity desired in a given length of cloth and the length of a cloth section or "rack" varies with the requirements of the customer or with the use to which the cloth is to be put. Manifestly, it is always desired to have the racks or lengths of cloth and the elastic qualities thereof uniform throughout the same web or as nearly uniform as possible, but it is difficult to obtain such uniformity for the following reasons: The threads are drawn from the warp beams by the knitting movements of the machine, and the withdrawal of unequal lengths of thread is accomplished by applying different brake tension to the different beams, in a manner well understood, so that the beams will have different surface speeds in response to the pulling action of the unwinding threads. By surface speed of the warp beams is meant the surface speed of the outer convolutions of the material carried by the beams. At the beginning of the knitting operation, the brake tension on the several beams is therefore adjusted differently to permit the desired relative difference in surface speed and to allow different lengths of threads to be withdrawn from said beams during the knitting movements of the machine, and this difference in lengths of thread should be retained throughout the knitting of the web, if the latter is to have uniform qualities. It will be understood, however, that, as the threads are unwound, the diameters of the beams become smaller and

smaller and this has to be compensated for by adjusting the tension on the beams at rather frequent intervals. Heretofore, the judgment of the operator based on haphazard methods has been relied upon to obtain the proper amount of compensation but almost invariably, at the end of a run, a considerable amount of thread will be left over on one beam when the thread on another beam has been used up. That means waste and it also means a certain amount of non-uniformity in the qualities of the web or a departure from the standard desired. This problem is a long-standing one in the art, and it is the object of this invention to provide a method and means for more accurately ascertaining, during the knitting operation, if the beams are rotating at the right speeds to feed the proper lengths of thread, and to ascertain the effect of any adjustment of the brake tensions on the speeds of the beams.

The method and means of the invention are illustrated in a preferred form in the accompanying drawing in which:

Fig. 1 is a diagrammatic view in perspective of certain parts of a tricot warp knitting machine with the devices relating to the present invention shown associated therewith; and

Fig. 2 is a fragmentary detail view in elevation of a part of the counting mechanism employed in the invention.

The warp beams (of which there may be two or more) are shown conventionally and are indicated at 1 and 2, said beams being provided with friction brakes 3 and 4, receiving brake bands 5 and 6, one end of each of which bands is anchored at 7 or 8 on framework 9, and the other end of each of which bands has a threaded portion 10 or 11, passing freely through an opening 12 or 13 in said framework. Wing nuts 14 or 15 engage said portions 10 or 11 and, with framework 9 acting as an abutment, serve to allow the operator to independently vary the tension of the brake bands against the friction brakes in a manner well understood in the art.

A indicates a marking station and B and C denote two observation stations. X is a thread drawn from warp beam 1 and is guided over bars 16 and 17, through guide 18 past marking station A, through guide 19, through guide B2 to observation station C and thence through guide C1 to the so-called slay point of the knitting machine, said machine being diagrammatically indicated at K. Y is another thread drawn from warp beam 2 and is guided over bar 17, through guide 18, past marking station A, through guide

20 to observation station B and thence through guide B1 to the slay point of the machine. Z indicates the cloth produced by the needles (not shown) in knitting the threads. It will, of course, be understood that there are a great many more threads coming from the warp beams but, as it is unnecessary to describe the well-known knitting operation of the machine, such other threads can be disregarded for the purpose of the present disclosure. It is also obvious that more than two warp beams can be employed, in which case a thread from each warp beam would be led past the marking station to appropriate observation stations.

21 indicates the main shaft of the machine, here making one revolution to each knitting movement, and this shaft carries a cam 22 that actuates an automatic counting or registering device, in this instance by the following means: Cam 22 actuates a bell-crank 23 that is mounted to rock on support 24, and said bell-crank, by means of cam surface 25, actuates a lever 26, pivoted at 27, carrying a pivoted pawl 28 at its free end. 29 indicates a ratchet wheel rotatably mounted on shaft 30, which ratchet wheel is engaged by pawl 28 to be intermittently advanced thereby, one step at a time for each knitting movement or each revolution of shaft 21. 31 is a stop pawl for ratchet wheel 29. 32 is a pin or tooth carried by ratchet wheel 29, which pin 32 engages a ratchet wheel 33 rotatably mounted on shaft 34, said ratchet wheel 33 advancing one step or tooth to each revolution of ratchet wheel 29. 35 is a stop pawl for ratchet wheel 33. The counting device, represented by ratchet wheel 33, thus registers a predetermined cycle of knitting movements of the machine, which cycle, for purposes of illustration, may consist of four hundred and eighty knitting movements. Such a cycle is called a "rack" and corresponds to a section or "rack" Z1 of cloth.

At marking station A is located a marking device which, here, is constructed as follows: 36 is a fountain, containing a washable or removable ink or dye, located in rear of threads X and Y as viewed in Fig. 1, and this fountain is provided with a wick 37 of absorbent material. 38 is a rock-shaft, mounted in bearings 39, and carrying a spring arm 40 provided at its outer end with a marker 41 located on the outside of threads X and Y as viewed in Fig. 1. Marker 41 is located opposite wick 37, and running threads X and Y normally pass freely between said marker and wick without being touched by either. When, however, rock-shaft 38 is actuated, marker 41 strikes a quick blow at threads X and Y bringing them momentarily against wick 37 and thus marks both of the running threads simultaneously without interfering with their advancing movement. By reason of spring arm 40, marker 41 immediately rebounds and does not again touch the threads until rock-shaft 38 is again actuated.

Suitable means, controlled by counting device or ratchet 33, are provided to actuate, at regularly recurring intervals, rock-shaft 38 and thus the marking device, which means, in this instance, are as follows: Mounted fast on a rock-shaft 42 is an arm 43 having a cam surface 44, and this arm is pivotally connected at its outer end to a rod 45 that, in turn, is pivotally connected to link 46 mounted fast on rock-shaft 38. A spring 47, anchored at 48 on the framework and connected to arm 43, tends to urge arm 43 into its lowermost position and, through the connections described, rock-shaft 38 into one position.

Ratchet 33 carries a pin 49 that, once to each revolution of ratchet 33 and therefore once to each predetermined cycle of knitting movements of the machine, engages cam 44 and lifts arm 43 against the tension of spring 47. Cam 44 has a gradual rise and a sudden drop as shown and, in advancing one tooth or step, ratchet 33 first lifts said arm 43 and then abruptly drops it, thereby actuating rock-shaft 38 and, by reason of spring arm 40, gives a sudden jerk to marker 41 causing said marker to engage and mark the running threads. At the same time, rock-shaft 42 is moved by arm 43 causing hammer 50 to strike gong 51 thus notifying the operator that a predetermined cycle of knitting movements has been completed. Ratchet 33 carries a second pin or tooth 52 that engages ratchet 53 to advance it one tooth and thus register the completion of a "rack" on a dial, but this part of the mechanism need not be described further.

The method of the invention is as follows: Let us assume, for the purpose of illustration, that the length of thread X, to be supplied during a predetermined cycle of knitting movements, is sixty inches, and that the length of thread Y, to be supplied during the same cycle, is forty inches, and that these two threads (and of course numerous other similar threads) are to be knitted into a cloth section X1 of definite length such as six inches. It will be apparent that thread X must run at a higher speed than thread Y and that, therefore, warp beam 1 will have a different surface speed from that of warp beam 2. The relative angular speeds of the two warp beams will depend upon the difference in diameter of said beams and could under certain conditions be equal. Observation station B is located a distance (as thread Y runs) from marking station A equal to that length of thread Y which is to be supplied during one predetermined cycle of knitting movements, and observation station C is located a distance (as thread X runs) from marking station A equal to that length of thread X which is to be supplied during the same predetermined cycle of knitting movements. Threads X and Y, running at different speeds, are guided past marking station A where they are simultaneously marked once to each predetermined cycle of knitting movements or at regularly recurring intervals. Said threads are then guided to the two observation stations C and B, one thread to one and the other to the other observation station, over paths so differing in length that, notwithstanding the differences in speed and length of the two threads, the marked portions or spots X1 and Y1 thereof will arrive simultaneously at observation stations C and B, after an interval corresponding to a cycle of knitting movements, provided that said warp beams rotate at speeds to supply the desired predetermined lengths of thread during said cycle of knitting movements. If spots X1 and Y1 do not arrive at observation stations C and B simultaneously, then the brake tension on the warp beam or beams is adjusted to compensate for the deviation from the correct speed. Spots X1 and Y1 are due to arrive at the observation stations at the time the succeeding marking of the threads occurs at the marking station. It could happen that said spots would arrive simultaneously at said observation stations and still be running at incorrect speeds, that is: earlier or later than the succeeding marking on the threads. To guard against this and other contingencies, gong 51 is provided, the sounding of which noti-

ties the operator of the completion of the cycle of knitting movements and therefore of the time when spots X_1 and Y_1 should arrive at the observation stations. The word "simultaneous" has been used in respect to the arrival of spots X_1 and Y_1 at the observation stations, but it will, of course, be understood that no mathematically exact adjustment is likely to be obtained; all that can be expected is at best a very close approximation. Observation stations B and C can be located in different positions, so long as their distance from marking station A, as the threads run, is equal to the lengths of thread desired during each cycle of knitting movements. Said observation stations could be located a distance from the slay point, as the threads run, equal to the lengths of thread desired during each cycle of knitting movements, that is to say: observation stations C and B could be equidistant, as the threads run, from marking station A and the slay point indicated diagrammatically adjacent sinkers Z_2 by a dot Z_3 . It is preferred, however, to have said observation stations C and B as close as possible to the slay point of the machine in the manner shown in Fig. 1. From an inspection of this view, it will be seen that at observation station B two guides are located, one marked B_1 through which thread Y is guided directly downward to the slay point and, another, marked B_2 , for guiding thread X to observation station C at which place a guide C_1 is located through which said thread X is guided. From guide C_1 said thread X is directed obliquely to the slay point, so that the path between C_1 and the slay point is longer than the path between B_1 and the slay point, to thereby compensate for the difference in speed of the two threads.

Although, as has been pointed out, numerous threads are fed from the warp beams, only two threads are in this instance marked, and the marking thus produced will show itself in the cloth as at Y_2 and X_2 . These two marks will be in alinement transversely of the cloth, and successive markings such as Y_2 or X_2 will indicate a cloth section or rack Z_1 produced during each cycle of knitting movements. The operator therefore has an additional check in that, while the cloth is on the run, he can measure the distance between two marks Y_2 or between two marks X_2 , and thus ascertain if a cloth section, produced during any previous cycles of knitting movements, is of the right length—in the instance given, six inches. It will also now be apparent that spots or indication marks Y_2 and X_2 will enable the operator to count the number of sections of the cloth or web produced during a plurality of cycles of knitting movements as well as to ascertain the length of a cloth section produced during any cycle of knitting movements.

I claim:

1. In the manufacture of cloth containing threads drawn from two warp beams to supply, during a predetermined cycle of knitting movements of the knitting machine, predetermined different lengths of thread to be knitted into the same predetermined length of cloth, the method of ascertaining the lengths of threads so fed and thus the speeds of said beams during said cycle of knitting movements, which consists in guiding two threads running at different speeds, one drawn from one and the other from the other of said warp beams, to a marking station; simultaneously marking said running threads at said station at regularly recurring intervals corre-

sponding to recurrent cycles of knitting movements of the machine; and guiding said threads so marked to two observation stations, one thread to one observation station and the other thread to the other observation station, over paths so differing in length that, notwithstanding the difference in speed and length of the two threads, the marked portions of said threads will arrive simultaneously at the two observation stations after an interval corresponding to a cycle of knitting movements, provided said warp beams rotate at speeds to supply said predetermined lengths of thread during said cycle of knitting movements.

2. In the manufacture of cloth containing threads drawn from two warp beams to supply, during a predetermined cycle of knitting movements of the knitting machine, predetermined different lengths of thread to be knitted into the same predetermined length of cloth, the method of ascertaining the lengths of threads so fed and thus the speeds of said beams during said cycle of knitting movements, and of ascertaining the length of a section of cloth produced during any predetermined cycle of knitting movements, which consists in guiding two threads running at different speeds, one drawn from one and the other from the other of said warp beams, to a marking station; simultaneously marking said running threads at said station at regularly recurring intervals corresponding to recurrent cycles of knitting movements of the machine; guiding said threads so marked to two observation stations, one thread to one observation station and the other thread to the other observation station, over paths so differing in length that, notwithstanding the differences in speed and length of the two threads, the marked portions of said threads will arrive simultaneously at the two observation stations after an interval corresponding to a cycle of knitting movements, provided said warp beams rotate at speeds to supply said predetermined lengths of thread during said cycle of knitting movements; and guiding said threads from the observation stations to the slay point of the machine over paths so differing in length that, notwithstanding the differences in speed and length of the two threads, the marked portions of said threads will appear in lateral alinement and at predetermined intervals in the cloth to thereby mark it into sections of a predetermined length.

3. In the manufacture of cloth containing threads drawn from two warp beams to supply, during a predetermined cycle of knitting movements of the knitting machine, predetermined different lengths of thread to be knitted into the same predetermined length of cloth, the method of ascertaining the length of a section of cloth produced during any predetermined cycle of knitting movements which consists in guiding two threads running at different speeds, one drawn from one and the other from the other of said warp beams, to a marking station; simultaneously marking said running threads at said station at regularly recurring intervals corresponding to recurrent cycles of knitting movements of the machine; guiding said threads so marked from said station to the slay point of the machine over paths so differing in length that, notwithstanding the differences in speed and length of the two threads, the marked portions of said threads will appear in lateral alinement and at predetermined intervals in the cloth to thereby mark it into sections of a predetermined length, provided

said warp beams rotate at speeds to supply said predetermined lengths of thread during the production of said cloth sections.

4. In a knitting machine for the production of cloth containing threads drawn from two warp beams that supply, during a predetermined cycle of knitting movements of the machine, different lengths of thread running at different speeds to be knitted into the same predetermined length of cloth, a counting device to automatically register the number of knitting movements of the machine in a predetermined cycle of movements; means to guide two threads running at different speeds, one drawn from one and the other from the other of said warp beams, to a marking station; a marking device, located at said marking station, to simultaneously mark said two running threads; and means, controlled by said counting device, to actuate said marking device to mark said running threads at regularly recurring intervals.

5. In a knitting machine for the production of cloth containing threads drawn from two warp beams that supply, during a predetermined cycle of knitting movements of the machine, different lengths of thread running at different speeds to be knitted into the same predetermined length of cloth, a counting device to automatically register the number of knitting movements of the machine in a predetermined cycle of movements; means to guide two threads running at different speeds, one drawn from one and the other from the other of said warp beams, to a marking station; a marking device, located at said marking station, to simultaneously mark said two running threads; means, controlled by said counting device, to actuate said marking device to mark said running threads at regularly recurring intervals; and means to guide said threads so marked to two observation stations, one thread to one observation station and the other thread to the other observation station, over paths so differing in length that, notwithstanding the differences in speed and length of the two threads, the marked portions of the two threads will arrive simultaneously at the two observation stations after an interval corresponding to a cycle of knitting movements, provided said warp beams rotate at speeds to supply said predetermined lengths of thread during said cycle of knitting movements.

6. In a knitting machine for the production of cloth containing threads drawn from two warp beams that supply, during a predetermined cycle of knitting movements of the machine, different lengths of thread running at different speeds to be knitted into the same predetermined

length of cloth, a counting device to automatically register the number of knitting movements of the machine in a predetermined cycle of movements; a thread marking device located in the path of running thread; and means, controlled by said counting device, to actuate said marking device to mark said running thread at regularly recurring intervals corresponding to a cycle of knitting movements.

7. In a knitting machine for the production of cloth containing threads drawn from two warp beams that supply, during a predetermined cycle of knitting movements of the machine, different lengths of thread running at different speeds to be knitted into the same predetermined length of cloth, a counting device to automatically register the number of knitting movements of the machine in a predetermined cycle of movements; means to guide two threads running at different speeds, one drawn from one and the other from the other of said warp beams, to a marking station; a marking device, located at said marking station, to simultaneously mark said two running threads; means, controlled by said counting device, to actuate said marking device to mark said running threads at regularly recurring intervals; and means to guide said threads so marked to the slay point of the machine over paths so differing in length that, notwithstanding the differences in speed and length of the two threads, the marked portions of the two threads will arrive simultaneously at said slay point and will appear in the cloth as two series of indication marks, the marks in each series being spaced longitudinally.

8. In a knitting machine for the production of cloth containing threads drawn from two warp beams that supply, during a predetermined cycle of knitting movements of the machine, different lengths of thread running at different speeds to be knitted into the same predetermined length of cloth, a counting device to automatically register the number of knitting movements of the machine in a predetermined cycle of movements; a thread marking device located in the path of running thread; means, controlled by said counting device, to actuate said marking device to mark said running thread at regularly recurring intervals corresponding to a cycle of knitting movements; and means to guide said thread to the slay point of the machine whereby the marks on the thread will appear as a series of indications, spaced longitudinally, in the knitted cloth.

FRANK J. KAUFMANN.
